UNITED STATES PATENT OFFICE.

JOHN ROSE, OF PHILADELPHIA, PENNSYLVANIA, ASSIGNOR TO NEWARK RIVET WORKS, OF NEWARK, NEW JERSEY, A CORPORATION OF NEW JERSEY.

GEAT FOR UMBRELLAS.

SPECIFICATION forming part of Letters Patent No. 732,782, dated July 7, 1903.

Application filed October 10, 1900. Renewed June 1, 1903. Serial No. 159,617. (No model.)

To all whom it may concern:

Be it known that I, JOHN ROSE, a citizen of the United States, residing at Philadelphia, in the county of Philadelphia and State of Pennsylvania, have invented certain new and useful Improvements in Umbrella-Frames; and I do declare the following to be a full, clear, and exact description of the invention, such as will enable others skilled in the art to which it appertains to make and use the same, reference being had to the accompanying drawings, and to the letters of reference marked thereon, which form a part of this specification.

15 This invention relates to umbrella-frames; and it relates particularly to the means for attaching the braces or stretchers to the ribs.

In constructing umbrellas capable of being closely rolled for convenient handling or to 20 be introduced into a case of small diameter when not in use it is desirable that the braces or stretchers should be within the ribs when the frame is folded and that there should be no projections on the outer faces of the ribs 25 liable to distort and wear the cover when after the frame is folded the cover is wrapped around it or when the umbrella is open and the cover is stretched and brought into close contact with the outer surfaces of the frame.

30 The object of the present invention is to provide means for connecting the braces or stretchers of umbrella-frames to grooved or trough ribs which shall when in place be entirely within the ribs presenting no projections to come into contact with the cover when the latter is applied to the frame.

Further, the object of the invention is to provide means for connecting braces or stretchers to the ribs of umbrella-frames which 40 shall be simple and cheap in construction, easily applied, and which shall strengthen the frame at the point at which it is applied rather than weaken it, as is the case when the ribs are pierced and pins or rivets are 45 used to connect the parts.

The invention consists, essentially, of the means for connecting an umbrella brace or spreader to a grooved or trough rib, comprising two wings or plates connected together 50 apart from and side by side of each other

and having opposing recesses opening at their opposing sides.

Further, the invention consists of various novel details of construction, substantially as hereinafter described and claimed.

The invention is illustrated in the accompanying drawings, in which—

Figure 1 is a perspective view of my invention, being shown in place to connect a brace or spreader and an umbrella-rib, a 60 small section only of each the rib and the brace or spreader being shown. Fig. 2 is a perspective view of my form of geat removed from the parts to which it is applied in use. Fig. 3 is a view representing a section of 65 umbrella-rib, showing the means for holding the geat in position for use; and Fig. 4 is a view showing the end of a brace or spreader of a form adapted for use in connection with my invention.

In the drawings, A represents an umbrella-rib, which is of the usual form of metal grooved or troughed rib.

The geat, the form and arrangement of which forms the principal feature of the invention, 75 is composed principally of the two wings or plates B B, suitably connected to hold them in proper relation to each other. In the embodiment of the invention illustrated the two wings and the connection-piece b are made in 80 one continuous piece, the connecting-piece being of a form to fit closely to the curved inner face of the rib. Each wing or plate has in it an opening b' extending outward to a point about middle of the wing or plate. 85 The opening is broad at its base and tapers outward to a point b², where it is of a size to receive and confine and at the same time to allow free movement of one of the projections c from the brace or spreader C. The 90 portion b, connecting the wings of the geat, has in it an opening b³ adjacent to the openings b' to receive the end of the brace or spreader when the latter is in position. Indentations b⁴ are formed in the wings along their outer 95 faces to receive inward-bent portions a of the ribs, by which the geats are retained in place in the ribs.

The outer ends of the braces or spreaders C are flattened to allow them to lie longitudi- 100

dinally in the geat when the frame is folded, and extending from each side of the flattened end is a projection *c*. Each projection is adapted to enter an opening in one of the 5 wings *B* to form a hinge upon which the brace or spreader turns in opening or closing the umbrella-frame.

In connecting a rib and a brace or spreader the outer end of the latter is introduced into 10 the geat, the projections being brought to rest in the small ends of the openings in the wings, and the geat is then placed in the groove in the rib. After this the edges *a* of the rib adjacent to the indentations *b*⁴ are bent inward 15 into the indentations to securely retain the wings in place. With the parts thus assembled the juncture of the rib and spreader is made permanent, free movement is allowed the spreader, a smooth rib is presented for 20 contact with the cover, and none of the parts are weakened by piercing it for the reception of a pin or rivet.

Having thus described my invention, what I claim as new, and desire to secure by Letters 25 Patent, is—

1. The means for connecting an umbrella brace or spreader to a grooved or trough rib, comprising two wings or plates connected together apart from and side by side of each

other and having opposing recesses opening 30 at their opposite sides, substantially as described.

2. The combination of a grooved or trough rib, a spreader having a projection extending from each side of its end, and two plates 35 connected together apart from and alongside each other and arranged along the inner faces of the groove of the rib and having opposing recesses facing the bottom of the groove of the rib, the edges of the rib being bent inward to confine the plates, substantially as described.

3. The combination with a grooved or trough rib having its edges provided with inward-bent portions, of the two wings 45 connected to each other and provided with openings extending from their inner edges outward, and having indentations in their outer edges receiving the inward-bent portions of the ribs, and a brace or spreader having projections extending from each side of its outer end, substantially as described.

In testimony whereof I affix my signature in presence of two witnesses.

JOHN ROSE.
